SLIDABLE SASH SUPPORT REPLACEMENT
DEVICE

August Ruesch, New York, N. Y.

Application March 22, 1938, Serial No. 197,328

2 Claims. (Cl. 16—202)

This invention relates to slidable sashes as used in connection with windows in buildings, and more particularly to the flexible supports whereby they are held suspended in adjustment for height.

Such supports commonly consist of cords or chains connected at one end within recesses in the sash sides, passed over pulleys set in the window frame and attached to weights counterbalancing the sash.

Cords eventually wear out and chains break, endangering the glass in the sash by shock in falling, and further require considerable effort to adjust, as the connection to the counterweight becomes ruptured, rendering it necessary to replace the support.

Such renewal has hitherto necessitated removal of the sash from the frame, requiring the service of an artisan involving expense, delay and trouble.

It is therefore an object of the invention to provide a simple device for replacing a new cord or chain without removal of the sash from the window.

A further feature is in the provision of an appliance to be incorporated in the window sash whereby substitution of its supports is easily effected.

These important objects are accomplished by the novel construction and arrangement of parts hereinafter described and illustrated in the accompanying drawings, constituting a material part of this disclosure, and in which:

Figure 1 is a front elevational view of the upper part of a common type of window showing the application of an embodiment of the invention.

Figure 2 is an enlarged fragmentary sectional view of the window frame taken on line 2—2 of Figure 4.

Figure 3 is an edge elevational view thereof.

Figure 4 is a top plan view of the same.

Figure 5 is a transverse sectional view taken on line 5—5 of Figure 2.

Figure 6 is a similar view taken on line 6—6 of Figure 2.

Figure 7 is a plan view of a guard plate in detail.

Figure 8 is a longitudinal sectional view taken on line 8—8 of Figure 9.

Figure 9 is a side view of a channelled guide for the support means.

Figure 10 is a longitudinal sectional view of the support anchorage looking on line 10—10 of Figure 11.

Figure 11 is a side view thereof.

Figure 12 is a sectional view taken on line 12—12 of Figure 13.

Figure 13 is a side view of a modified form of support anchorage.

Figure 14 is a side view of a still further modification in support anchorage. 5

Figure 15 is a transverse sectional view taken on line 15—15 of Figure 16.

Figure 16 is a sectional view, similar to Figure 2, but showing a modified arrangement of parts. 10

Referring in greater detail to the drawings, the window frame, shown in Figure 1, consists of the usual uprights 20 connected at their upper ends by a cross-piece 21.

These uprights are channelled to receive sash 15 22—23 enclosing the common glass pane 24, the window frame being provided with pockets in which are sash pulleys 25 over which are trained flexible supporting elements, as the chains 26 or cords, their lower ends being attached to pendant 20 weights, not shown.

The upper side elements 22 of the sash have undercut longitudinal recesses 28 centrally of their width and open, as at 29, at their outer sides. 25

The top element 23 is also recessed to receive flat plates 30, held by screws 31 and have notches 32 in their outer ends.

Disposed in the recesses 28 are bars 33 having 30 at their upper ends out-turned flanges 34 through which one of the screws 31 passes, the flanges being overlaid by the plates 30.

The lower ends of the bars 33 have thickened terminals 35 on their outer sides, provided with recesses 36 through which extend pins 37, these pins adapted to engage the last link in the sash chain 26. 35

Fixed midway the length of the bars 33 are screw-studs 38 to extend from their rear sides 40 and engage in sockets 39 set in the sash sides 22.

In order to guide the chains, a filler 40 is disposed in each recess 28, these bars having longitudinal recesses 41 in their outer surfaces; claws 42, at the lower ends of the bars 40, straddle the chains, and at their upper ends are passages 43 for the insertion of a pin or the like when maneuvering the chains. 45

In the modification shown in Figures 12 and 13, the bar 33 is formed with a flat forward extension 50 45 at its lower end in which is fixed a screw-eye 46 to engage the end of a cord 47 in a manner considered plainly apparent.

The remaining Figures 14, 15 and 16, show a modified form of screw stud 48 engageable in 55

a socket 39 and at the ends of the fillers 33 are projections 50, above which are openings 51 to receive knots on the ends of the cords 47, the cords passing upwardly between prongs 53.

5 The fillers 40 are also provided with channels 54 to clear the heads of the screw-studs 48, as best seen in Figure 16.

10 The operation of replacing defective cord or chain is accomplished by raising the sash, removing the plate 30 to permit releasing the fillers 40, whereupon the bars 33 may be swung outwardly to allow removal of the old cord or chain and attachment of the support to be substituted.

15 Although the foregoing is descriptive of the preferred embodiment of the invention, it will be apparent that minor changes may be made in its construction, without departing from the scope of the claims hereto appended.

20 Having thus described the invention, what is claimed as new and desired to secure by Letters Patent, is:

1. In a device for attaching a counter-weighted flexible connection to a window sash, said sash

having an undercut longitudinal groove in the upper portion of its side edge, a bar fixed in the sash groove, a dowel set in said bar to engage a corresponding opening in the sash, means at the bottom of said bar to engage said flexible connection, a filler strip having a grooved outer face through which said connections pass, and means to retain said bar within the groove.

2. In a device for attaching a counter-weighted flexible connection to a window sash, said sash having an undercut longitudinal groove in its edge, a bar disposed in said groove, said bar having an integral, angular pad at its upper end secured to the upper member of said sash, a dowel set in said bar to engage the sash, means at the bottom of said bar to engage said flexible connection, a removable filler disposed in the groove to fill the remaining space therein and having a recessed face for the passage of said flexible connection, and a plate over the ends of said bar and filler fixed on the upper element 10 15 20 of said sash.

AUGUST RUESCH.
